US0D1085914S

(12) **United States Design Patent** (10) Patent No.: **US D1,085,914 S**
(45) Date of Patent: ** Jul. 29, 2025

(54) **TEMPERATURE SENSOR**

(71) Applicant: **Google LLC**, Mountain View, CA (US)

(72) Inventors: **Phan Thao Benno Dang**, San Francisco, CA (US); **Sung Kyun Bai**, San Jose, CA (US); **Dongkyu Lee**, Castro Valley, CA (US); **Maj Isabelle Olsson**, Sunnyvale, CA (US); **Eun Hee Jo**, San Jose, CA (US)

(73) Assignee: **Google LLC**, Mountain View, CA (US)

(**) Term: **15 Years**

(21) Appl. No.: **29/913,610**

(22) Filed: **Oct. 5, 2023**

(51) LOC (15) Cl. **10-04**

(52) U.S. Cl.

USPC **D10/52**

(58) Field of Classification Search

USPC D10/50, 52, 46, 70, 75
CPC .. F24F 11/47; F24F 11/58; F24F 11/00; F24F 11/52; F24F 11/64; G05D 23/1904; G05D 23/1917; G05D 23/1923

CLAIM

The ornamental design for a temperature sensor, as shown and described.

DESCRIPTION

FIG. 1 is a front, right, top perspective view of a temperature sensor according to a first embodiment of our new design;
